UNITED STATES PATENT OFFICE.

THEODORE M. BECHERER, OF BELLEVILLE, ILLINOIS.

SPEED-INDICATOR.

No. 863,014.

Specification of Letters Patent.

Patented Aug. 13, 1907.

Application filed August 17, 1906. Serial No. 331,026.

To all whom it may concern:

Be it known that I, THEODORE M. BECHERER, a citizen of the United States, residing at Belleville, in the county of St. Clair, State of Illinois, have invented 5 certain new and useful Improvements in Speed-Indicators; and I do hereby declare the following to be a full, clear, and exact description of the invention, such as will enable others skilled in the art to which it appertains to make and use the same.

10 This invention relates to speed indicators and has for its object to provide a mechanism of this character which may be readily adjusted to suit varying conditions and which, though thoroughly efficient in action, will be of extremely simple construction.

15 The invention has for its object furthermore to provide means for adjusting the indicating mechanism so that a specified size of pulley will not necessarily have to be used.

Broadly speaking the invention resides in the provision of a shaft, a centrifugal speed actuating means 20 for the speed indicating mechanism upon the shaft, means for adjusting the said centrifugal actuating means, and a speed indicating mechanism including an arm with which the shaft is engaged at one of its 25 ends, the arm being adjustable with respect to the shaft to adapt the mechanism to different sizes of pulleys.

In the accompanying drawings, Figure 1 is a front elevation of the invention, Fig. 2 is a rear elevation of the said indicating mechanism, the rear face of the casing being broken away, and, Figs. 3 and 4 are detail vertical transverse sectional views on the lines 3—3 and 4—4 respectively of Fig. 2.

Referring more specifically to the drawings the numeral 5 denotes a shaft which is journaled in suitable 35 bearing brackets 6 which may be attached to any convenient support such as the bed of an automobile or the like.

The numeral 7 denotes a collar which is engaged upon the shaft 5 and is held in fixed position thereon 40 by means of adjusting nuts 8 and 9 which are engaged upon the shaft 5 upon opposite sides of the said collar and in engagement therein, the said shaft being screw threaded as at 10 for a portion of its length for engagement of the nuts 8 and 9 thereon, it being understood 45 that by adjusting the said nuts the collar 7 may be correspondingly adjusted upon the shaft. The purpose of this adjustment will hereinafter be explained.

A pulley 11 is splined upon a sleeve 11' which is loosely engaged upon the shaft and is provided with 50 an integral collar portion 12 and connected at one of their ends to the said collar portion 12 are leaf springs 13 which are connected at their opposite end to the collar 7 and which are each provided intermediate its ends with a ball 14. The opposite end of the sleeve 55 to its collar portion 12 is engaged through the bracket 6 and is flanged as at 13' to prevent it moving away

from the bracket. A belt 15 is engaged with the pulley 11 and with a shaft or axle (not shown).

The indicating mechanism comprises a casing 16 in which is mounted for rocking movement, a segmental plate 17 having its curved edges provided with a series of rock teeth 18 which meshes with a pinion 19 upon a shaft 20 which is journaled at its ends in the front and rear face of the casing 16. A pointer or hand 21 is also engaged upon the shaft 20 and registers with numbers 65 upon a dial 22 which is disposed upon the front face of the casing.

The shaft 5 extends through an opening in one side of the casing 16 and has its end inwardly of the casing seated in a recess formed in a collar 24, which is provided with a bore for the reception of a threaded arm 25 of a member 27 which is formed of the arm 25 and an arm 28 which extends at right angles to the said arm and is provided at its end with a right angularly turned portion 29 which works in a slot 30 formed in the segmental plate 17. A nut 26 is engaged upon the threaded arm 25 and bears against the underside of the collar 24 and serves as a means whereby the member 27 may be adjusted vertically to vary the position of its portion 29 in the slot 30. The collar 24 is provided with a 70 flanged extension 31 which works in a guide 32 upon the rear face of the casing 16 and serves to support the said collar and the member 27.

From the above it will be observed that rotation of the shaft 5 will cause the same to move longitudinally 75 thereby resulting in a movement in a corresponding direction of the member 27 and a consequent rocking movement of the segmental plate 17. This movement of the said plate will turn the shaft 20 and thereby indicate the speed of rotation of the shaft from which the 80 shaft 5 is driven or the speed of travel of the vehicle to which the indicator is applied, and it is obvious that by adjusting the member 27 vertically, the rocking movement of the plate 17 may be regulated to suit various sizes of pulleys.

It will be understood that I do not desire to be limited to the exact details of construction shown and described, for obvious modifications will occur to a person skilled in the art.

What is claimed is:

A device of the class described comprising a shaft arranged for rotation and for sliding movement, a pulley which is stationary in regard to said shaft, centrifugal means for slidably moving the shaft when rotated, a member connected with the shaft, a rocking member engaged by the last named member, means for adjusting the first named member with respect to the rocking member, a hand shaft and gear connections between said rocking member and said hand shaft.

In testimony whereof, I affix my signature, in presence 110 of two witnesses.

THEODORE M. BECHERER.
